STEAM POWER SYSTEM

Application filed December 1, 1928; Serial No. 323,178, and in Great Britain February 14, 1928.

This invention relates to steam power installations and its object is to effect economy in the operation thereof by utilizing the exhaust steam, from say the auxiliary machinery.

To the attainment of this object, the present invention provides improved means whereby said exhaust steam can be re-heated by the boiler gases and so revivified for further use.

Said means comprises, in its simplest form a sinuous pipe unit adapted to be supported in position on a boiler front inside the uptake, and inlet and outlet connections for the exhaust steam to be passed through the pipe unit.

Preferably the heater is hinged or pivotally supported in such manner that it can be readily turned from its normal position to give access to the boiler fire tubes behind the same. For this purpose the heater may be journalled in bearing brackets secured to the boiler front, and angle strips may be attached to the heater to rest against said front in order to space the heater therefrom so that it normally occupies a position inclined to the boiler face.

The sinuous pipe unit constituting the heater may be built up of any desired number of separate pipe-lengths arranged parallel to one another in spaced relationship, and connected by U-shaped headers.

If the steam power installation is operated by a battery of two or more boilers fitted with exhaust steam heater units in accordance with the present invention, said units may be connected in series to form one continuous heater. Obviously, the outlet of one unit would be connected with the inlet of the next unit.

Conveniently, the inlet to the heater is arranged to communicate with a valve by means of which the exhaust steam from the auxiliaries can be directed, at will, to the heater or to a waste steam pipe leading, if desired, to the main condenser, whereas the heater outlet is arranged to communicate with a pipe leading to the low pressure engine of the installation through a constant-pressure valve. Branches from said pipe may lead to the feed-water heater or the evaporator or both,

and there may be fitted a safety valve set to blow off at a predetermined pressure, also a pressure gauge. A branch may be led from said pipe for general heating purposes, such as heating cabins.

53

We will now describe embodiments of our invention, by way of example, with reference to the accompanying drawings, whereon:—

Fig. 1 is a partly diagrammatic view showing the heater according to the invention in plan, as applied to a marine three boiler installation;

Fig. 2 is a front view of the heater as shown in Fig. 1;

Fig. 3 is a front view of the heater as applied to a twin boiler installation;

Fig. 4 shows one method of supporting the pipe unit on the boiler front inside the uptake;

Fig. 5 shows another method of supporting the pipe unit.

Reference 1 represents the boiler shell and 2 represents the fire tubes; the parts of the boilers shown in the drawings are at the uptake, or front, end. The inlet 3 to the heater 4 is arranged to communicate with a valve 5 by means of which the exhaust steam coming from the auxiliaries by pipe 6, can be directed, as desired, to the heater by the pipe 3 or to a waste steam pipe 7 leading for instance to the condenser. The steam passes through the sinuous piping of the heater 4 in the manner shown in Figs. 2 and 3; the hot gases from the fire tubes, instead of passing directly away to the chimney, pass between and around the pipes of the heater 4 thereby partially reheating the exhaust steam. After being thus heated, the steam passes by the heater outlet pipe 8 to a branch pipe communicating through valves with the various appliances in which the reheated steam is used.

As shown in the example illustrated in Fig. 1, pipe 9 leads to the low pressure engine of the installation through a constant pressure valve 10, pipe 11 leads to the evaporator; pipe 12 takes steam for general purposes such as heating cabins, etc.; pipe 13 leads to the feed heater. The pipe 8 may be provided with the usual devices such as a safety valve and pressure-gauge.

With reference to Fig. 3 it will be seen that a convenient arrangement of piping for a twin boiler installation is that each of the two boilers is equipped with a heater in the form of a sinuous pipe unit arranged in four parallel rows in the uptake, all the piping being connected in series. The adjacent ends of pipes are connected together by headers; thus, a header connects the first and second pipe lengths at one end, a header connects the second and third pipe lengths at the opposite side of the boiler face, and a third header connects the third and fourth pipe lengths at the same end that the first and second pipe lengths are connected. The adjacent ends of the first and fourth pipe lengths not connected in this manner constitute inlet and outlet connections, respectively, for one boiler piping unit.

Two units built up in the manner described are mounted one on each of the two boiler fronts with their inlet and outlet ends adjacent, and the outlet from one unit is joined to the inlet of the other at 22 so as to form one continuous heater having a single inlet 3 and a single outlet 8.

The units are each supported by brackets 14, on the boiler front, and are held in an inclined position relative to the fire tube plate by angle strips such as 16 (Fig. 4) which rest against said plate.

With this construction exhaust steam flows in a sinuous path first through one heater unit and then through the other to the aforesaid pipe 8 leading to the low pressure engine, etc. During the passage of the steam through the heater its temperature is raised by the hot boiler gases rising in the boiler uptake and flowing between the spaced pipe lengths constituting the heaters.

Fig. 4 shows an arrangement for supporting a heater unit so that it can be turned up, away from the boiler front to give access to the fire tubes. The piping is carried in a framework comprising frame members 17 bolted together and hinged by one of the upper pipes, or by bearing pins, in a bearing bracket 18. The angle strip 16 as aforesaid rests against the boiler face to hold the piping at an angle thereto in order to allow free exit of the gases from the fire tubes.

Another method of supporting the piping in the uptake and free of the fire tubes is shown on Fig. 5. The piping is carried in cast iron blocks 19 which are bolted together and the whole is held in position by being bolted to stay rods 20 passing through a fire tube and supported by an angle 21 attached to the smoke box.

Obviously, the invention can be applied to a single boiler or to a battery of more than two boilers.

A convenient mode of connection for the piping when applied to three boilers is shown on Fig. 2. As before the pipes are all con-

nected in series, and the fourth pipe length of the first unit is joined to the second pipe length of the second unit, while the first and fourth pipe length of the second unit are joined respectively to the first and fourth pipe lengths of the third unit; the separate pipe lengths are also connected by U-shaped headers as before and the inlet and outlet connections to and from the combined heater are between the first and second units.

Although we have referred to heater units comprising four rows of pipe lengths, there may be any desired number of rows or return bends, or any desired number of layers of pipe lengths. Here the "rows" are disposed transversely to the direction of flow of the hot gases and the "layers" extend in the direction of flow thereof.

When a pipe unit composed of a plurality of rows and layers of pipes, is used, preferably the layers of pipe lengths in each row are connected in series by split bends, while the rows are interconnected by solid bends.

We have described our invention with reference to certain preferred embodiments but we desire it to be understood that modifications may be made and that no limitations upon our invention are intended other than are imposed by the scope of the appended claims.

We claim:—

1. In a steam power system including a flue-tube boiler, an exhaust steam heater comprising a plurality of separate pipe lengths and headers connecting the lengths in series, to form at least one sinuous pipe unit, said unit being located in the boiler uptake and extending directly across the discharge ends of the upper flue tubes whereby the hottest flue gases issuing from the flue tubes play on an extensive surface of the pipe unit, and means for angularly supporting said unit on the boiler front.

2. In a steam power system including a battery of flue-tube boilers, an exhaust steam heater comprising a plurality of separate pipe lengths and headers connecting the lengths in series, to form a plurality of series-connected sinuous pipe units located in the boiler-uptakes and extending directly across the discharge ends of the upper flue tubes whereby the hottest flue gases issuing from the flue tubes play on an extensive surface of the pipe units, and means for angularly supporting said units on the uptake ends of the boiler shells.

In testimony whereof we affix our signatures.

STEPHEN LEYSHON WYNDHAM.
JAMES NEWBY WYNDHAM.
